UNITED STATES PATENT OFFICE

2,030,374

DRILL BIT

Herman Louis Kless, Houston, Tex.

Application May 22, 1933, Serial No. 672,331
Renewed August 21, 1935

7 Claims. (Cl. 255—61)

The present invention relates to new and useful improvements in well drill bits of the fluid discharge type and has for one of its important objects to provide, in a manner as hereinafter set forth, a bit of this character embodying a novel construction and arrangement through the medium of which clogging of the fluid passages when the bit is in operation will be prevented.

Other objects of the invention are to provide a drill bit of the aforementioned character which will be simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a drill bit constructed in accordance with the present invention.

Figure 2 is a view in edge elevation thereof.

Figure 3 is a bottom plan view.

Figure 4 is a vertical sectional view through a lower portion of the bit.

Referring now to the drawings in detail, it will be seen that the embodiment of the invention which has been illustrated comprises a body 1 from which the usual threaded shank 2 rises. On opposite sides, the body 1 has its vertical marginal portions concaved, as at 3, and formed to provide cutting edges 4 which ream and smooth the walls of the hole, said cutting edges 4 being inclined forwardly toward their lower ends, as illustrated to advantage in Figure 2 of the drawings. Spaced notches or recesses 5 are formed in the vertical side edges of the body 1.

The body 1 is also formed, on opposite sides, to provide forwardly projecting substantially wedge-shaped or triangular cutting edges 6 which parallel the reaming edges 4, as best seen in Figure 2 of the drawings. The advanced cutting edges 6 serve to break up the cuttings in a manner to facilitate the washing of said cuttings out of the hole.

Extending through the bit from end to end thereof are downwardly diverging fluid passages 7 which, as illustrated to advantage in Figures 3 and 4 of the drawings, communicate with the trailing faces of the side portions of said bit through the medium of rearwardly directed passages 8, said passages 8 being substantially behind

the cutting edges 6. Branch outlets 9 communicate with the fluid passages 7 for washing the cutting edges 6.

It is believed that the many advantages of a drill bit constructed in accordance with the present invention will be readily understood, particularly by those skilled in the art, and although the preferred embodiment of the invention is as illustrated and described, it is to be understood that changes in the details of construction and in the arrangement of parts may be resorted to which will fall within the scope of the invention as claimed.

What is claimed is:

1. A drill bit comprising a body having fluid passages therein communicating with the lower end of the bit and extending to the trailing faces of said bit on opposite sides of its longitudinal axis, and reaming cutters on the vertical edges of the body, each cutter having a concaved front face and a rearwardly and inwardly sloping outer edge, portions of the passages opening out through the trailing faces of said cutters.

2. A drill bit comprising reaming cutters on the vertical edges thereof, breaking cutters on the forward face portions of the bit on opposite sides of the longitudinal axis thereof, said breaking cutters parallel to the reaming cutters, said bit having fluid passages therein communicating with the lower end thereof and having portions opening out through the trailing faces of the reaming cutters.

3. A drill bit comprising reaming cutters on the vertical edges thereof, breaking cutters on the forward face portions of the bit on opposite sides of the longitudinal axis thereof, said breaking cutters parallel to the reaming cutters, said bit having fluid passages therein communicating with the lower end thereof and provided with angularly extending portions communicating with the trailing faces of the bit, the bit further having fluid branches therein communicating with the passages for washing the breaking cutters.

4. A drill bit comprising reaming cutters on the vertical edges thereof, breaking cutters on the forward face portions of the bit on opposite sides of the longitudinal axis thereof, said breaking cutters parallel to the reaming cutters, said bit having fluid passages therein communicating with the lower end thereof and provided with angularly extending portions communicating with the trailing faces of the bit, the bit further having fluid branches therein communicating with the passages for washing the breaking cutters.

ters, the vertical edges of the bit having spaced recesses therein.

5. A drill bit of the class described comprising a narrow body of considerable width and having 5 its vertical side edges beveled to provide a cutting edge at one side of one face and a second cutting edge at the side edge of the other face and said body having fluid passages therein extending out to the lower end of the body and 10 having portions at their lower ends opening out through the trailing faces of the cutters.

6. A drill bit of the class described comprising a narrow body of considerable width and having 15 its vertical side edges beveled to provide a cutting edge at one side of one face and a second cutting edge at the side edge of the other face and said body having fluid passages therein opening out to the lower end of the body and having

portions at their lower ends opening out through the trailing faces of the cutters, each cutting edge having vertically spaced recesses therein.

7. A drill bit of the class described comprising a narrow body of considerable width and having 5 its vertical side edges beveled to provide a cutting edge at one side of one face and a second cutting edge at the side edge of the other face and said body having fluid passages therein opening out to the lower end of the body and 10 having portions at their lower ends opening out through the trailing faces of the cutters, and a vertically arranged substantially V-shaped projection on each face of the body, said projections being spaced outwardly from the axis of the body, 15 the apexes of said projections forming breaking cutters.

HERMAN LOUIS KLESS.
